[54] GARMENT HANGER BODY

[75] Inventors: John H. Batts, East Grand Rapids; Everett L. Duester, Zeeland, both of Mich.

[73] Assignee: John Thomas Batts, Inc., Zeeland, Mich.

[] Term: 14 Years

[21] Appl. No.: 178,552

[22] Filed: Aug. 15, 1980

[51] Int. Cl. .... D6—08

[52] U.S. Cl. D6/254; D6/257

[58] Field of Search D6/113, 247-257; 211/113, 119; 223/85, 87-96

[56] References Cited

U.S. PATENT DOCUMENTS

D. 151,978 12/1948 Glavies D6/249

D. 195,445	6/1963	Warmath	D6/254
D. 206,199	11/1966	Zuckerman	D6/254
D. 247,150	2/1978	Duester	D6/257
2,464,324	3/1949	Levin	223/91
4,226,345	10/1980	Szabo	223/91

*Primary Examiner—B. J. Bullock
Attorney, Agent, or Firm—Price, Heneveld, Huijzena & Cooper*

[57] CLAIM

The ornamental design for a garment hanger body, substantially as shown and described.

DESCRIPTION

FIG. 1 is a front elevational view of a garment hanger body showing our new design;

FIG. 2 is a top plan view thereof;

FIG. 3 is a bottom plan view thereof;

FIG. 4 is an end elevational view thereof, both ends being identical.

The rear is unornamented.

U.S. Patent

Feb. 15, 1983

Des. 267,920

Fig. 1.

Fig. 2.

Fig. 3.

Fig. 4.